[57] CLAIM

The ornamental design for a medical equipment storage tray, as shown.

DESCRIPTION

FIG. 1 is a top plan view of a medical equipment storage tray showing my new design;

FIG. 2 is a bottom plan view thereof;

FIG. 3 is a side elevational view thereof, the opposite side being substantially a mirror image thereof;

FIG. 4 is a cross-sectional view taken through the lines 4—4 of FIG. 1; and

FIG. 5 is an end elevational view, the opposite end being substantially a mirror image thereof.
